C. GUGGENBUEHLER,
TOOL FOR FACILITATING THE ADJUSTMENT OF THE DRIVING SHOES OF LOCOMOTIVES.
APPLICATION FILED SEPT. 27, 1920.
1,423,795. Patented July 25, 1922.

Inventor
Carl Guggenbuehler
By his Attorney
Mac. O'Dowd

UNITED STATES PATENT OFFICE.

CARL GUGGENBUEHLER, OF NEWARK, NEW JERSEY.

TOOL FOR FACILITATING THE ADJUSTMENT OF THE DRIVING SHOES OF LOCOMOTIVES.

1,423,795.

Specification of Letters Patent. Patented July 25, 1922.

Application filed September 27, 1920. Serial No. 413,205.

To all whom it may concern:

Be it known that I, CARL GUGGENBUEHLER, citizen of Germany, residing at Newark, in the county of Hudson and State of New Jersey, have invented certain new and useful Improvements in Tools for Facilitating the Adjustment of the Driving Shoes of Locomotives, of which the following is a specification.

10 This present invention has reference to tools for the adjustment of the driving shoes in the bearings of locomotives or the like relative to the driving boxes of the wheels, as described and shown in my Patent 15 #1,327,468 dated January 6, 1920.

The construction of the tool of said patent has the drawback that it is only applicable to standard size locomotives. When the size of the lower edge of the bearing frame differs from the standard size my patented tool 20 cannot be used.

The object of this improvement is to provide a construction which will allow an adjustment of the tool to fit differently sized 25 locomotives.

With this object in view my invention consists in the novel construction, combination and arrangement of parts as will be hereinafter fully described and defined in 30 the appended claims.

In the accompanying drawing in which similar reference characters denote corresponding parts, Fig. 1 is a side elevation of a part of the bearing frame of the locomotive, showing two of the driving shoes designed for one driving box clamped in position by my tool; Fig. 2 is a perspective view of my improved clamp; Fig. 3 is a perspective view of a detail of said clamp and Fig. 40 4 a section on line 4-4 of Fig. 2.

Referring specifically to the drawing *a* denotes the frame provided with the bearing *b* for the driving box (not shown) and the driving shoes *c*.

45 The clamp forming the subject of the present invention and serving for temporarily engaging the driving shoes *c* and hold them in position, while the locomotive is being lowered onto the wheels to place the driving box therein, consists of a hollow bar or block *g*, the upper face of which is shaped to conform with the usual shape of the lower

edge of the bearing frame, the said face being offset at one end to form a vertical shoulder *g'* which will bear against the side of the 55 downwardly projecting portion *a'* of the bearing frame while the offset part *g''* will bear against the lower face of the part *a'*. The upper face of the block *g* is provided with a longitudinal slot *g''* for the passage 60 of the usual screw bolts *d* projecting from the lower edge of the bearing frame and generally serving for the fastening of the binder bars (not shown).

The block *g* is fastened to the frame by 65 the screw bolts *d*, on which I apply specially constructed nuts *e* adapted to fit the usual two sizes of bolts *d*.

Thus far the construction of my tool is similar to the one described and shown in 70 my aforesigned patent.

The improvement of the invention resides in that the end member *j* serving to support the driving shoes *c* when the tool is in position, instead of being directly applied to 75 the block *g*, as in the patent aforesigned, is attached to a member *h* which is slidably supported in the block *g*. To this end the offset portion *g''* is provided with a longitudinal groove *g''*, in which the member *h* 80 is slidably mounted. The forward end of said member *h* is provided with a cross groove *h'* into which the reduced lower end *j'* of the member *j* is adapted to be removably engaged. The rear end *h''* of the slide 85 *h* is cut out centrally and longitudinally to clear the opening *g''* in the block *g* through which passes one of the screw bolts *d*.

Equipped with this adjustable member *h* the tool at once becomes applicable to locomotives both of standard and irregular sizes. Thus, if the part *a'* of the frame is longer than the length of the offset portion *g''* of the block then the slide *h* is adjusted 90 to conform with the particular length of 95 the part *a'*. A set screw *h* working in a threaded bore *g''* of the offset portion *g''* serves to securely hold the slide *h* in its adjusted position.

What I claim and desire to secure by Letters Patent is:

A tool for facilitating the adjustment of the driving shoes of locomotives as per claim 1, said tool including a block having an off-

set portion to conform with and bear against the lower surface of the bearing frame, and which has openings for the free passage of the bolts projecting from the said frame, a longitudinally slidale member mounted in said offset portion, a vertical member removably engaged in said slidale member and serving to engage the lower edge of a

driving shoe, and means for temporarily clamping said tool to the bearing frame. 10

In testimony whereof I affix my signature in presence of two witnesses.

CARL GUGGENBUEHLER.

Witnesses:

MAX D. ORDMANN,

JOSEPH T. McMAHON.
